DESIGN FOR A WINDMILL

Henry N. Edens, Freeport, Ill., assignor to Stover
Manufacturing & Engine Co., Freeport, Ill., a
corporation of Illinois

Application June 26, 1939, Serial No. 85,709

Term of patent 14 years

To all whom it may concern:

Be it known that I, Henry N. Edens, a citizen
of the United States, residing at Freeport, in the
county of Stephenson and State of Illinois, have
invented a new, original, and ornamental Design
for a Windmill, of which the following is a spec-
ification, reference being had to the accompan-
ying drawing forming part thereof.

In the drawing:

Fig. 1 is a side view of the upper portion of
a windmill embodying my new design;

Fig. 2 is a side view of the vane portion only;

Fig. 3 is a top plan view thereof, and

Fig. 4 is a side elevational view of the complete
windmill.

The dominant features of the design are those
shown in full lines and comprise a windmill vane
of the configuration shown having opposing edges
substantially parallel.

I claim:

The ornamental design for a windmill, sub-
stantially as shown and described.

HENRY N. EDENS.
